UNITED STATES PATENT OFFICE.

FREDERICK B. HIBBARD, OF PHILADELPHIA, PENNSYLVANIA.

STEAM-BOILER.

No. 834,131.

Specification of Letters Patent.

Patented Oct. 23, 1906.

Application filed June 27, 1905. Serial No. 267,225.

To all whom it may concern:

Be it known that I, FREDERICK B. HIBBARD, a citizen of the United States, and a resident of the city and county of Philadelphia, State of Pennsylvania, have invented certain new and useful Improvements in Steam-Boilers, of which the following is a specification.

My invention relates to improvements in steam-boilers, the objects of my invention being to eliminate the objectionable crown-sheet usually employed in vertical and locomotive boilers and to furnish an internally-fired return-fire tube-boiler the fire-box of which will be surrounded by water, giving a greater and more effective heating-surface in proportion to the size of the boiler than has heretofore been the case, which will have the necessary height to secure proper combustion, which will not have any flat surfaces liable to be prematurely burned out, and which will from its cylindrical form throughout stand very high pressures.

My improved boiler is illustrated in the accompanying drawings, forming part of this specification, in which—

Figure 1 is a vertical central sectional elevation of my improved boiler, and Fig. 2 a section of Fig. 1 on line A B.

My boiler consists of two parts—a vertical part *a* and a horizontal part *b*. The front end of the horizontal part *b* enters the vertical part *a* and, together with a wall *c*, of fire-brick or other suitable material, forms the top of the fire-box *d*, which is located in the lower part of the vertical member *a*.

e represents the grate-bars in the lower end of the fire-box, and *f* is the fire-door.

As will be seen from the drawings, the vertical member *a* of the boiler is furnished with double walls forming a space *g*, the lower portion of which is filled with water and the upper portion of which forms a steam-space. The water-space between the walls of the vertical member *a* of the boiler is connected with the water-space of the horizontal member *b*. The steam-spaces of the two members are also in communication, and hence the water stands at the same level in both portions of the device and circulates freely from one part to the other.

The heat and products of combustion from the fire-chamber *d* pass to the tubes *h* in the horizontal member *b* of the boiler, thence to the box *j* at the rear of this member, thence through tubes *i* to the upper portion *k* of the

vertical member *a*, and thence to the stack. The gases after passing through the upper tubes *i* come in contact with the steam-space in the upper end of the vertical member *a* and serve to superheat the steam in this space before passing to the stack. Steam may be drawn off through a pipe *l*, connected with the steam-space of the part *a*, or from any other suitable and convenient place.

m represents hand-holes through which access may be had to the interior parts of the boiler for purposes of cleaning.

n is a cleaning-door at the lower end of the smoke-chamber *k*.

An inspection of the drawings will show that the top of the fire-chamber *d* is formed by the inwardly-projecting portion of the part *b* and the wall *c*, these parts taking the place of the usual crown-sheet. Scale, sediment, rust, &c., which ordinarily fall upon the crown-sheet and which are responsible for the contraction and expansion which results in leaks around the tubes, have in my construction no flat sheet to fall upon to cause damage of this character. They must be caught by the lower side of the shell *b* or must fall to the bottom of the space *g* between the walls of the vertical part *a* of the boiler. In either case they can easily be removed through conveniently-situated hand-holes *m*.

My boiler is cylindrical throughout, has a very great and effective heating-surface, and is provided with steam and water spaces of capacity to secure the best results in service.

Having thus described my invention, I claim and desire to secure by Letters Patent—

1. In a steam-boiler, in combination, an internally-fired vertical member and a horizontal member, the latter of which is provided with two sets of flues and one end of which projects into and forms part of the top of the fire-box in the vertical member, and a wall or partition extending from the inwardly-projecting end of said horizontal member from points between said series to the inner sides of said vertical member completing the top of the fire-box and separating the outgoing and incoming flues in said horizontal member, the portion of said horizontal member below said partition projecting into said fire-box.

2. In a steam-boiler, a vertical member, a horizontal member entering one side of the vertical member and projecting therein to a

point adjacent the center of the vertical member, and a partition secured at a point substantially central of the diameter of said horizontal member and having its edges 5 abutting the inner wall of the vertical member and the portions of said horizontal member which project in said vertical member.

3. A steam-boiler embodying a vertical member having a fire-box, a horizontal member projecting in the vertical member to have 10 the lower portion thereof overlie said fire-box

and constitute a part of the top thereof, said horizontal member having two series of flues therein, and a wall disposed between said projecting portions of said horizontal member and said vertical member to complete the top of the fire-box. 15

FREDERICK B. HIBBARD.
